UNITED STATES PATENT OFFICE.

JOHN N. COLBY, OF NEW LONDON, CONNECTICUT, ASSIGNOR OF ONE-HALF
TO JOSEPH H. AMIES, OF SAME PLACE.

UMBRELLA.

SPECIFICATION forming part of Letters Patent No. 289,229, dated November 27, 1883.

Application filed August 28, 1883. (No model.)

To all whom it may concern:

Be it known that I, JOHN N. COLBY, a citizen of the United States, and a resident of New London, Connecticut, have invented certain Improvements in Cane-Umbrellas, of which the following is a specification.

My invention consists of certain improvements in the combined cane and umbrella for which I applied for Letters Patent of the 10 United States on the 9th day of May, 1883, serial number of application 94,365.

My present improvements relate to the runner, to the device for securing the stretcher thereto, to the connection between the runner 15 and its surrounding ferrule, to the device for retaining the runner when the umbrella is raised, and to the means for securing the cover of the umbrella to the ribs.

In the accompanying drawings, Figure 1 is 20 a vertical section of part of the umbrella; Fig. 2, a sectional plan on the lines 1 2; Fig. 3, a perspective view of the runner; Fig. 4, a perspective view of one of the stretcher-connections; Fig. 5, a sectional view of the retainer for the runner when the umbrella is 25 raised; and Fig. 6, a view of the tip end of one of the ribs, showing the method of attaching the cover; Fig. 7, a perspective view of one of the cover-retaining rings. All of these views are 30 drawn to an exaggerated scale.

A is the stick of the umbrella, which has longitudinal grooves for the reception of the hollow ribs B and stretchers D, as in the former case.

35 F is the runner, which consists of a corrugated tube adapted to fit snugly to the grooved stick, and free to slide thereon. This tube is seamless, being formed by drawing or forcing a seamless tube through dies of the proper 40 shape, thus producing very cheaply a stronger and more accurate runner than can be made by casting it, or by bending up and soldering or brazing a strip of sheet metal. In each of the ribs a of the runner is formed a central 45 recess, d, and to the grooves b of the runner are adapted the V-shaped stretcher-bars G, each of which has opposite wings, f, adapted to the recesses in the ribs a on the opposite sides of the groove containing the stretcher- 50 bar, so that the latter is secured vertically to

the runner, and is compelled to move therewith. The wings f are slightly elastic, and bear with a yielding pressure upon the ferrule H, which incloses the runner, the friction being sufficient to cause the movement of the 55 runner with the ferrule when there is no undue opposition to this movement—that is to say, no more than is caused by the opening of the umbrella, for instance. When the movement of the runner is prevented, however— 60 as, for instance, when the ribs are confined and prevented from spreading—the ferrule can, with a slight extra effort, be moved independently of the runner, as may be necessary to cause the same to confine the tips of the ribs, 65 as in Fig. 1, or to release said ribs when it is desired to spread them. The objectionable screw or bayonet-joint connection between the runner and its ferrule is dispensed with, the construction of the device being thereby cheapened and the operation of the same simplified. 70 The runner fits so snugly to the grooved stick that the friction between the two may be relied upon to retain the runner in position when the umbrella is spread; but for additional security I provide one of the grooves of the stick with a spring-finger, g, Fig. 5, which, when the runner is elevated, bears against the upper end of the same, or against 75 the projecting end of one of the stretcher-bars, or both, and increases the friction. The ferrule H acts directly upon the tips of the ribs to retain the same, whether the ribs are bare, as when the device is used for a cane, or are provided with a cover, as when the cane 80 is formed into an umbrella, the same adjustment of the ferrule being made in either case. To permit the ferrule to act upon the tips of the ribs, the cover x must be secured to the latter some distance above the tips; hence I 85 reduce each rib at and near the end, so as to form a shoulder, w, Fig. 6, the cover x being provided at the outer edge with as many rings y as there are ribs, each ring being slipped over the tip and finding a bearing against the 90 shoulder w, as shown in Figs. 6 and 7. Each ring has an eye, y', by which it is secured to the umbrella; but the rings may be plain, if desired. Instead of relying upon the elastic 95 wings f of the stretcher-bars for insuring 100

proper frictional contact between the runner and ferrule H, the runner may have special elastic wings for this purpose; but, on the score of economy, the double use of the wings f is preferred.

I claim as my invention—

1. The seamless longitudinally-corrugated runner-tube F, as set forth.
2. The seamless longitudinally-corrugated runner-tube F, having external recesses, d, as set forth.
3. The combination of the corrugated runner F, having recesses d, with the stretcher-bars G, having wings adapted to said recesses, as set forth.
4. The combination of the runner with the ferrule H, held in position thereon by friction, as set forth.

5. The combination of the runner, the ferrule H, and the stretcher-bars G, having elastic fingers f, as set forth.

6. The combination of the stick A and the runner with the spring-finger g, adapted to retain the runner by friction, as set forth.

7. The combination of the ribs having shoulders w above the tips with the cover x, having rings y, adapted to bear against the shoulders, as set forth.

In testimony whereof I have signed my name to this specification in the presence of two subscribing witnesses.

JOHN N. COLBY.
